Primary Examiner — Michelle E. Wilson

Assistant Examiner — Clese Moore, Jr.

(57) **CLAIM**

The ornamental design for a motorcycle left side spoiler as shown and described.

DESCRIPTION

FIG. 1 is a left side elevational view of a motorcycle left side spoiler showing our new design;

FIG. 2 is a top plan view of the motorcycle left side spoiler; FIG. 3 is right (inner) side elevational view of the motorcycle left side spoiler;

FIG. 4 is a perspective view, from below, of the motorcycle left side spoiler;

FIG. 5 is a view, from above and behind, of the motorcycle left side spoiler; and,

FIG. 6 is a view, from above, of the motorcycle left side spoiler.

Features shown in broken lines are unclaimed subject matter and form no part of the claim to be protected. An ornamental design for a motorcycle right side spoiler is a mirror image of that shown.

1 Claim, 6 Drawing Sheets
